UNITED STATES PATENT OFFICE.

FRANK HILLIARD WATSON, OF JONESBORO, ARKANSAS.

VIOLIN-PIANO.

1,117,288.

Specification of Letters Patent.

Patented Nov. 17, 1914.

Application filed December 21, 1912. Serial No. 737,979.

To all whom it may concern:

Be it known that I, FRANK HILLIARD WATSON, a citizen of the United States, and a resident of Jonesboro, in the county of 5 Craighead and State of Arkansas, have invented a new and Improved Violin-Piano, of which the following is a full, clear, and exact description.

The invention relates to violin pianos, 10 such as shown and described in the Letters Patent of the United States, No. 846,268, granted to me on March 5, 1907.

The object of the present invention is to provide a new and improved violin piano 15 arranged to permit of playing either the violin or the piano or both at the same time with the same keys, and to insure a proper contact between the broad surfaces of the endless traveling bands and the vibratory 20 piano strings with a view to produce full and clear violin sounds.

For the purpose mentioned use is made of an endless crossed band moving across a vibratory string and having its crossed 25 portion adjacent to the said string, the flat surfaces of the crossed portion being approximately parallel with the said string, and means for deflecting one run of the crossed band to move one flat surface thereof in engagement with the string to sound 30 the same.

A practical embodiment of the invention is represented in the accompanying drawings forming a part of this specification, 35 in which similar characters of reference indicate corresponding parts in all the views.

Figure 1 is a front elevation of the violin piano, parts being broken out; Fig. 2 is an 40 enlarged cross section of the same on the line 2—2 of Fig. 1; Fig. 3 is a sectional front elevation of the same on the line 3—3 of Fig. 2 and showing more particularly the strings and the crossed portions of the endless bands for sounding the strings; Fig. 4 is an enlarged sectional plan view of a number 45 of the endless bands and the means for moving the same into engagement with the strings, the section being on the line 4—4 of Fig. 5; Fig. 5 is a cross section of the same 50 also showing the pneumatic means for shifting the crossed portion of the endless bands; Fig. 6 is a plan view of the pneumatics connected with the shifting means for the endless bands; Fig. 7 is a front elevation of the

swing rod for engagement with the hammer jacks to render the piano action inactive; Fig. 8 is a cross section of the piano action and the means for throwing the hammer jacks out of action; Fig. 9 is a similar view 60 of the same and showing the parts in position at the time the hammer jacks are out of action; and Fig. 10 is a cross section of the keyboard and one of the valves of the pneumatic mechanism.

Within the piano casing A are arranged treble and bass strings B, B' connected at their upper ends to tuning pins C held on the wrest plank D. The lower ends of the strings B, B' are secured to the hitch pin 70 C' arranged on the metallic frame E. Both the wrest plank D and the metallic frame E are mounted on the back frame F which also supports the sounding board F' located in the rear of the strings B and B'. The 75 strings B and B' are adapted to be engaged by hammers G' and dampers G² forming part of the piano action G, of any approved construction, so that further detailed description of the same is not deemed necessary, it being sufficient to state that the 80 hammers G' are actuated by the hammer jacks G³ mounted on wippens G⁴ connected with the piano keys G⁵ adapted to be played by the performer in the usual manner, so 85 that the hammers G' strike the strings B, B' and thereby sound the same. The dampers G² are controlled by the usual pedal G⁶ under the control of the performer, and a pedal G⁷ is employed and connected 90 with the action for reducing the throw of the hammers G'.

In order to produce violin sounds use is made of a plurality of endless crossed traveling bands H extending across the strings B, B' and having their crossed and flat portions disposed approximately parallel to the strings B, B' so that when one of the crossed portions of a band H is shifted sidewise of the left then one of its surfaces engages the 100 adjacent string and sounds the same. It is understood that the run of the band H used for sounding the string is disposed approximately at right angles to the string, as plainly shown in Fig. 5, and the vertical line 105 of the crossed or warped portion in the direction of the width thereof is approximately parallel to the string so that when the run is deflected a line contact is had between the deflected run and the string. The 110

endless crossed bands H pass around rollers arranged in front of the strings at the upper portions thereof and each band also passes around a grooved pulley located in the rear of the strings below the wrest plank D, as plainly indicated in Fig. 2. The roller I is provided at its ends with pulleys I' around which pass belts I² also passing around pulleys I³ secured on a longitudinal shaft I⁴ 10 journaled in suitable bearings on the sides of the casing A. On the shaft 14 (see Figs. 1 and 2) is secured a pulley I⁵ connected by a belt I⁶ with a pulley I⁷ secured on the motor shaft K' of a motor K of any approved construction, preferably, however, of the electric type, and mounted in the lower portion of the casing A. When the motor is running a rotary motion is transmitted to the shaft I⁴ which by the pulleys I³, I' and the belts I² rotates the grooved roller I so that a traveling motion is given to the endless crossed bands H. The shaft I⁸ of the grooved roller I is journaled in suitable brackets I⁹ attached to the wrest plank D, as plainly 20 shown in Figs. 1 and 2.

Each of the pulleys J has its shaft J' journaled in a bearing J² extending rearwardly on one face of the pulley, the rear end being attached to the free end of a spring J³ secured to a beveled block J⁴ attached to the rear of the wrest plank D by the use of a screw J⁵ or other fastening device. The upper end of the spring J³ is engaged by an adjusting screw J⁶ screwing in the 30 block J⁴ so as to impart a swinging motion to the spring J³ with a view to move the pulley J rearwardly so as to give more or less tension to the endless crossed band H. By arranging the bearings J² on 35 one face only of each pulley J, the band H can be readily placed in position on the pulley or removed therefrom for repairs or other purposes. Each band H is preferably made of specially treated rawhide, and the 40 ends are glued together. On the back of each band H is cemented a piece of rubber cloth so as to reinforce the band and make the same durable and noiseless. It is understood that the non-covered face of the band is 45 moved in engagement with the corresponding string B or B' to sound the same. By reference to Figs. 2 and 5 it will be noticed that the active face of the band remains outermost when passing around the roller I and the corresponding pulley J so that the active 50 face which is coated with rosin is not injured while the band passes around the roller I and the pulley J.

Normally, the crossed portions of each 60 band H are out of contact with the corresponding string, and in order to deflect one run of the band at the crossed portion so as to move the resinous surface of the said run in engagement with the string use is made 65 of the following device: One of the runs of

each band H is adapted to be engaged by a friction roller L journaled in a swing arm L' held on the upper end of a vertically-disposed shaft L² journaled near its upper end in a longitudinally adjustable bearing N, 70 while the lower end of each shaft L² is journaled in a fixed bearing N' secured at its ends to the sides of the casing A. Near the lower end of each shaft L² is secured a pulley L³ around which passes a flexible strip L⁴ secured to the pulley by a nail, screw or other fastening device L⁵ (see Fig. 6). One end of the flexible strip L⁴ is connected with a spring L⁶ held on the bearing N', and the other end of the flexible strip L⁴ is connected with the movable member of a pneumatic O mounted on a valve chest or suction chamber P extending longitudinally and secured to the sides of the casing A. The valve chest P is connected with a bellows Q 80 connected by a link Q' with the crank arm Q² of a shaft Q³ carrying a worm wheel Q⁴ in mesh with a worm Q⁵ secured to or formed on the motor shaft Q', so that when the motor K is running the bellows Q is actuated to draw the air out of the valve chest or suction chamber P. Each pneumatic O is connected by a port O' with the interior of the chest P, and the port O' is controlled by a valve P' held on a valve stem P² connected with a diaphragm P³ arranged over a chamber P⁴. From the chamber P⁴ leads a port O² connected by a flexible tube P⁵ with a valve seat R arranged on a keyboard G⁸ (see 90 Figs. 2 and 10). The valve seat R is normally closed by a valve R' held on one end of a lever R² fulcrumed on a bracket R³ attached to the keyboard bottom G⁸, and each key G⁵ is provided with a set screw R⁴ adapted to engage the forward end of the lever R² at the time the key is pressed so that a 100 swinging motion is given to the lever R² to open the valve R'. The lever R² is pressed by a spring R⁵ to normally hold the valve R' in closed position.

It is understood that when the valve R' moves into open position air passes through the valve seat R into the tube P⁵ and from the latter by way of the port O² into the chamber P⁴ to actuate the diaphragm P³ 115 and thereby move the valve P' into open position. When this takes place the interior of the corresponding pneumatic O is connected with the valve chest or suction chamber P by way of the port O' so that the pneumatic is collapsed. When this takes place a pull is exerted on the belt L⁴ to rotate the pulley L³ and consequently the shaft L², whereby a swinging motion is given to the arms L' to move the friction 120 roller L sidewise and thereby push the crossed portions of the endless band H in contact with the corresponding string B or B'. From the foregoing it will be seen that when any one of the keys G⁵ is pressed the 130

corresponding band H is actuated to sound the corresponding string B or B', and at the same time the same string is sounded by the corresponding hammer G' striking 5 that particular string. It is further understood that as long as the key is pressed the corresponding traveling band H remains in contact with the corresponding string to sound the same, and when the key is released 10 the several parts return to normal position owing to the action of the spring L⁶, which latter turns the shaft L² in a reverse direction to move the friction roller L out of engagement with the band H to 15 allow the latter to return to normal inactive position.

When it is desired to play the instrument without the violin effect, the motor K is stopped so that the suction in the valve 20 chest P ceases and consequently the pneumatics O remain dormant and the bands H remain out of engagement with the strings B, B'. When the keys G⁵ are now played the hammers G' strike the strings B, B' 25 and sound the same as in ordinary piano playing.

In order to render the hammer action inactive to permit of producing violin effects only, use is made of a rod or bar S 30 extending longitudinally in the rear of the hammer jacks G³ (see Figs. 7, 8 and 9). The rod or bar S is provided near its ends with arms S' journaled in bearings S² attached to the center rail G⁹ of the piano 35 action G, and the said rod or bar S is provided with an angular arm S³ connected by a link S⁴ with an arm S⁵ held on one end of a shaft S⁶ journaled in the lower portion of the casing A and connected with a pedal 40 S⁷, so that when this pedal S⁷ (see Fig. 1) is pressed then a swinging motion in a forward and downward direction is given to the rod or bar S so as to throw the hammer jacks G³ forwardly out of engagement with 45 the butts of the hammers G' (see Fig. 9). When the several parts are in the position described and the keys G⁵ are played then the hammers G' remain dormant while the bands H are moved in engagement with the 50 strings B, B', as above described, so that the said strings are sounded with violin effect. The turning motion of the shafts L² is limited by a pin L⁷ extending from the pulley L⁸ and adapted to abut against stop pins L⁹, held on the bottom bearing N' (see Fig. 6). The upper bearing N is mounted to slide side- 55 wise in bearings N² arranged on the wrest plank D (see Fig. 3) and one end of the bearing N is pressed on by a spring N³ and the other end is connected by a link N⁴ with a bell crank lever N⁵ pivoted to one side of the casing A, as plainly shown in Fig. 3. The bell crank lever N⁵ is connected by a link N⁶ with an arm N⁷ secured on 60 shaft N⁸ journaled in the lower portion of

the casing A and connected with a pedal N⁹ (see Fig. 1) under the control of the operator, so that when it is desired to sound the strings B, B' very loud by the bands H then the performer presses the pedal N⁹ to 70 shift the bearing N from the right to the left against the tension of the spring N³ so that the rollers L press the bands with more or less force against a corresponding tension in addition to the movement given to the rollers by the swing arms L'. When the performer releases the pedal N⁹ the spring N³ returns the bearing N to normal 75 position.

By reference to Fig. 4 it will be noticed 80 that groups of strings are used, the strings in each group being all tuned to the same pitch, each group being preferably composed of three strings in the treble and of two strings in the last two octaves of the 85 bass.

In practice, the hammer D' is of standard type and adapted to strike all the strings in the group including the string intended to be sounded by the bow band H, as above 90 explained.

By reference to Fig. 2, it will be noticed 95 that the crossing portions of the band H are located in the space immediately below the wrest plank D and the upper edge of the sounding board F' to allow of extending the sounding board F' into close proximity of the wrest plank to allow the use of comparatively short strings. The wrest plank D is preferably formed of an I-beam 100 filled on front and rear with wooden blocks, of which the front block is laminated to provide the desired strength for the pins C. By the use of the I-beam the wrest plank D is reinforced to such an extent that no sagging 105 is liable to take place and the strings after being tuned remain in proper tune for a considerable length of time.

Having thus described my invention, I claim as new and desire to secure by Letters Patent:

1. A musical instrument, comprising a vibratory string, an endless bow-band moving across the said string and having crossed runs, one of the runs passing in 115 close proximity to the string, and means for deflecting the said run to move it into engagement with the string.

2. A musical instrument, comprising a vibratory string, an endless bow-band moving across the said string and having crossed runs, one of the runs forming the string-sounding run and having a portion approximately parallel to and opposite the string, the said string-sounding run being 123 normally out of contact with the string, and means for deflecting the said string-sounding run to move the said portion into engagement with the said string.

3. A musical instrument, comprising a 125

vibratory string, a driven roller in front of the said string, a pulley in the rear of the said string, a crossed endless bow-band passing around the roller and pulley, the 5 crossed portions of the said band being adjacent the said string, and means for deflecting the run of the band adjacent the string to move the said run into engagement with the said string.

10 4. In a musical instrument, the combination of a piano-action having hammers, strings located to be sounded by the said piano action, a key board having keys for actuating the said piano action, endless 15 crossed traveling bands for engagement with the said strings, and actuating means controlled by the said keys and adapted to move one run of each of the said bands into engagement with the strings at the time the 20 hammers of the piano action sound the strings.

5. A piano provided with strings, endless crossed bands for sounding the piano strings, a driven roller around which pass 25 the said bands, pulleys around each of which passes one of the said endless crossed bands, individual suspended bearings in which the said pulleys are journaled, and spring supports for yieldingly suspending the said 30 bearings.

6. A piano provided with strings, endless crossed bands for sounding the piano strings, a driven roller around which pass 35 the said bands, pulleys around each of which passes one of the said endless crossed bands, individual suspended bearings in which the said pulleys are journaled, each bearing being open at one face of the corresponding pulley to allow of placing the band in position on the pulley or removing it therefrom, and spring supports for yieldingly suspending the said bearings.

7. In a musical instrument, the combination of a wrest plank, a sounding board having 45 its upper edge spaced from the said wrest plank, vibratory strings stretched over the said sounding board and connected with the said wrest plank, endless crossed bands moving across the said strings, the crossed 50 portions of the said bands passing between adjacent strings, and both runs of each band passing through the space between the said sounding board and the said wrest plank, and means for deflecting one run of 55 each of the crossed bands to move such deflected run into engagement with the corresponding string.

8. In a musical instrument, the combination of a piano action having hammers, piano 60 strings adapted to be sounded by the said hammers, keys for actuating the said hammers, endless crossed bands moving across the said strings and having the middle of their crossed portions adjacent the 65 strings, rock shafts carrying arms adapted

to engage the bands to deflect the latter to move the middle of the crossed portions of the said bands into engagement with the strings, pneumatics connected with the said shafts to rock the latter, and pneumatic 70 valve mechanism controlling the said pneumatics and provided with lever valves arranged under the keys and controlled by the same so that on pressing a key the corresponding hammer and the corresponding band simultaneously sound the same string. 75

9. A musical instrument provided with endless bands for sounding the piano strings, rock shafts having arms adapted to engage the said bands to press the latter into 80 engagement with the strings, a movable bearing for the ends of the shafts adjacent the said arms for the latter to move the bands with more or less force into engagement with the strings, and a fixed bearing 85 for the other ends of the said shafts.

10. A musical instrument provided with endless bands for sounding the piano strings, rock shafts having arms adapted to engage the said bands to press the latter into 90 engagement with the strings, a movable bearing for the ends of the shafts adjacent the said arms for the latter to move the bands with more or less force into engagement with the strings, a fixed bearing for 95 the other ends of the said shafts, and a pedal mechanism for actuating the said movable shaft bearing.

11. In a musical instrument, the combination of a wrest plank, a sounding board having 100 its upper edge spaced from the said wrest plank, vibratory strings stretched over the said sounding board and connected with the said wrest plank, endless crossed bands moving across the said strings, the crossed portions of the said bands passing 105 between adjacent strings, and both runs of each band passing through the space between the said sounding board and the said wrest plank, means for deflecting one run of each of the crossed bands to move such deflected run into engagement with the corresponding string, a driven roller in front of the said strings, and pulleys suspended from the said wrest plank, the said bands passing 110 around the said driven roller and individually around the said pulleys. 115

12. A musical instrument provided with endless bands for sounding the piano strings, rock shafts having arms adapted to engage the said bands to press the latter into engagement with the strings, pulleys on the said shafts, flexible strips engaging the said pulleys, springs attached to one end of the said flexible strips and pneumatics connected with the other end of the said flexible strips, and means to limit the turning motion of the said shafts.

13. A musical instrument provided with piano strings, a piano action for sounding 130

the said strings, keys for actuating the said piano action, endless traveling bands normally out of contact with the strings, deflecting means for the said bands to move 5 the latter into contact with the strings to sound the same, and pneumatic means controlling the said deflecting means and provided with valves arranged below the keys and adapted to be actuated by the said keys 10 so that on pressing a key the corresponding

string is simultaneously sounded by the piano action and the corresponding band.

In testimony whereof I have signed my name to this specification in the presence of two subscribing witnesses.

FRANK HILLIARD WATSON.
